KEY OPERATED SWITCH

Monroe Guett, Hartford, Conn., assignor to The Arrow-Hart & Hegeman Electric Company, Hartford, Conn., a corporation of Connecticut

Application January 3, 1931. Serial No. 506,456

4 Claims. (Cl. 200—42)

This invention relates to means for preventing unauthorized persons from operating electric switches. More particularly it relates to means for preventing anyone from operating a key-operated electric snap switch, with a screw driver, knife or other illegitimate operating device.

Heretofore key operated switches have been known and commonly used in many places where it was desirable to prevent promiscuous operation of electric switches, but many of these switches could be operated by well directed manipulation of screw drivers, bits of wire, nails, knives, etc.

It is an object of my invention to provide a switch which is readily operable by a special key provided therefor, but which can not be operated by any implements commonly employed to effect unauthorized operation of such switches.

Referring to the drawing:

Fig. 1 is a plan view of a switch embodying my invention.

Fig. 2 is a side elevation section view of the invention, taken on line 2—2 of Fig. 1.

Fig. 3 is an end elevation section view of the invention taken on line 3—3 of Fig. 2.

Fig. 4 is a bottom view of the housing employed in my invention to protect the operating mechanism.

Fig. 5 is a perspective view of the protecting housing employed in my invention.

Fig. 6 is a fragmentary detail view, in perspective, of the switch operating lever used in the embodiment of my invention shown in Figs. 1—5.

In the drawing, the switch mechanism is supported from a conventional switch supporting strap 10 having a depressed central portion 12 to which are secured depending legs 14 having V-notch bearings 16 cut into them to support a conventional U-shaped switching member 18.

This switching member is adapted to be thrown from one side of the bearing notches to the other by a tensioned spring 20 secured to the switching member and to an operating lever 22 which is mounted for oscillation between the legs 14 and 45 pivotally supported by an axle 24 passing through the ends of the legs 14. The operating lever is flat and its upper portion projects through an aperture 26 in the strap 10, between the legs 14.

A narrow curved plate 28 is secured to or may be 50 formed integrally with the upper portion of the operating member 22. The plate 28 is formed with an apertured ear 30 on each side of the plate, these ears being turned down from the plate toward the switch mechanism and the apertures 31 are adapted to receive portions of a switch

operating key 32 as will be more fully explained hereinafter.

In order that the operating lever 22 and plate 28 may not be engaged and moved by any implement other than the key 32 a protecting housing 60 34 is positioned over the plate 28 and is held in that position by a metallic housing-positioning plate 36 which is secured on top of the supporting strap 10 by screws 38 at each end of the plate, these screws coming through the usual insulating base (not shown) for snap switches of the type described.

The housing 34 (see Fig. 5) is made with a base portion 34a which is wider than the top portion 34b in order that the top portion may extend through a suitable rectangular aperture in the plate 36 and that the plate 36 may rest on the shoulders 34c (see Fig. 2) between the upper and lower portions. The bottom of the lower portion of the housing is channelled out to permit free oscillatory movement of the operating lever 22 and plate 28; and the upper portion of the housing is hollowed out to permit reciprocatory movement of the key 32. An I-shaped slot is formed through the top surface of the housing through 70 which the key 32 may be inserted. Beneath this slot and centrally located in the housing is a longitudinal guard rib 40 which prevents screw drivers, knife blades and the like from engaging the operating lever 22 and plate 28 to operate the switch. 75

The key 32, for operating the switch, has a forked end which is adapted to be inserted in the enlarged ends of the I-slot and to straddle the rib 40. The tines of the fork are adapted to fit 80 into the apertures 31 and engage with the ears 30 of the plate 28 to cause actuation of the operating lever 22 by the key, as the key is moved from one end of the I-slot to the other. 85

From the foregoing the operation of my switch 90 will be readily understood. Obviously the invention is not limited to the specific form of key and the specific embodiment of the invention I have shown. Many changes and modifications within the scope of the invention will occur to those skilled in the art. 95

I claim:

1. In a key operated switch adapted to be placed behind a conventional flush plate, switch operating mechanism movable in a plane perpendicular to the plane of the flush plate, protecting means for said switch mechanism having an opening into which an operating key may be inserted for actuation of the switch, means beneath said opening preventing direct access to 105 110

said operating mechanism and actuation thereof by illegitimate operating devices.

2. In a key operated switch, switch actuating mechanism, a protecting housing for said mechanism having a longitudinal slot through which a key may be inserted to operate the switch, a longitudinal rib extending below said slot and preventing direct engagement with and actuation of said operating mechanism by illegitimate operating devices, said key being movable lengthwise of said slot to operate the switch between its extreme positions.

3. In a key operated switch adapted to be placed behind a conventional flush plate, switch operating mechanism movable in a plane perpendicular to the plane of the flush plate, a supporting strap for said mechanism, a protecting housing

for said mechanism, said housing having an aperture for insertion of an operating key, means beneath said aperture preventing free access to and operation of said mechanism by illegitimate operating devices, and a plate engaging with said housing to hold it between the plate and said strap.

4. In a key operated electric switch, switch operating mechanism, a protecting housing for the operating mechanism having an I-shaped slot for reception of the switch operating key, and a rib beneath the longitudinally extending portion of the slot preventing access to and operation of said mechanism by illegitimate operating devices.

MONROE GUETT.
